Primary Examiner — Karen E. Eldridge Powers*Assistant Examiner* — Jasmine Mlinarcik(74) *Attorney, Agent, or Firm* — Arnold & Porter LLP(57) **CLAIM**

The ornamental design for a legging with a control layer, as shown and described.

DESCRIPTION

FIG. 1 is a front elevational view of a legging with a control layer;

FIG. 2 is a rear elevational view thereof;

FIG. 3 is a top plan view thereof;

FIG. 4 is a bottom plan thereof;

FIG. 5 is a right side elevational view thereof;

FIG. 6 is a left side elevational view thereof;

FIG. 7 is a front elevational view of a legging with a control layer, wherein the legging with a control layer has been turned inside-out;

FIG. 8 is a rear elevational view thereof;

FIG. 9 is a top plan view thereof;

FIG. 10 is a bottom plan view thereof;

FIG. 11 is a right side elevational view thereof; and,

FIG. 12 is a left side elevational view thereof.

The outline of the legging pant shown in broken lines illustrates environmental structure that forms no part of the claimed design. The broken lines within the bounds of the claimed design illustrate stitching, which is part of the claimed design.
